UNITED STATES PATENT OFFICE.

ARTHUR K. TAYLOR, OF ROLAND PARK, MARYLAND.

METHOD AND APPARATUS FOR OBTAINING REGISTERING FORMS.

1,199,941.

Specification of Letters Patent.

Patented Oct. 3, 1916.

Application filed May 4, 1914. Serial No. 836,339.

To all whom it may concern:

Be it known that I, ARTHUR K. TAYLOR, a citizen of the United States, and resident of Roland Park, Baltimore county, State 5 of Maryland, have invented certain new and useful Improvements in Methods of and Apparatus for Obtaining Registering Forms, of which the following is a specification.

10 The present invention relates to an improved method and apparatus for use in positioning cuts, dies, transfer impressions or type in printing, dieing and creasing or lithographic forms so that very accurate 15 registration of impressions from a plurality of forms will be insured.

In the preparation of such forms for use, for example, in multicolor work according to the method at present in common use, 20 an undesirable length of time and amount of labor is required. If the manipulations and adjustments required to properly position the printing surfaces of the form or forms to be used for other than the primary 25 impression, so that the necessary register of succeeding printings may be obtained, are carried out in the press room, the press must be idle for considerable periods of time during each job. Frequently very fine 30 or small misadjustment of a cut, die, or body of type will result in a considerable waste of material in addition to the loss in time and labor required to make the necessary correction.

35 By the method hereinafter described it is possible to prepare in the composing room, in a minimum amount of time, the several forms required for use in producing any particular piece of close register work, 40 in which a single sheet is necessarily subjected to a plurality of operations; and obtain substantially correct and perfect register of the different impressions.

In the accompanying drawing: Figure 45 1 is an elevation of a form of apparatus adapted to carry out the invention as applied to printing; Fig. 2 is a plan of one of the printing forms shown in Fig. 1; Fig. 3 is a similar view of the other form illustrated in Fig. 1; Fig. 4 is a diagrammatic view illustrating the action of the embodiment of the invention shown in Fig. 1; and Fig. 5 is a similar view showing a slightly different arrangement of parts for carrying 50 out the same method as the apparatus of Fig. 1.

The illustration of the several parts of the apparatus hereinafter referred to is more or less conventional in the drawings as the detail construction thereof can manifestly be varied within wide limits without departing from the scope of the invention. 60

Referring particularly to Figs. 1 to 4, A designates the ordinary compositor's imposing table or other suitable support adapted 65 to receive the chase or form B, containing the type or printing surfaces from which the first or primary impression is to be obtained, and a form or chase C for use in producing a subsequent impression on a 70 sheet previously printed from the form B.

On the table or support A is arranged an apparatus adapted to project an image or representation of more or less of the form B upon the form C so that type or 75 printing surfaces in the latter may be readily positioned therein so that impressions therefrom will be caused to accurately register with the spaces provided therefor in impressions obtained from the form B. 80 Said projection apparatus comprises two parallel, vertical, tubular members D, E connected at their upper ends by a tubular horizontal member F, mirrors or suitable reflecting surfaces (designated by G, H, in 85 Fig. 4) being arranged within the member F at an angle of 45°. A suitable source of light, for example an electric lamp, is arranged in a suitable housing adjacent the lower end of the upright D so that the portion of the chase or printing form B beneath said member D will be brightly 90 illuminated; and within the upright D is arranged a light projecting system shown in Fig. 4 as comprising two double convex 95 lenses I, J.

The apparatus is represented as resting upon suitable feet K (which are of such height and so arranged that the forms B, C may be adjusted as required to bring any 100 desired portions thereof into alinement with the tubular uprights D, C). As shown the lower end of the member E is situated in a horizontal plane somewhat above that including the lower end of the member D so 105 that the workman may obtain a clear view of the portion of form C beneath the tube E and that there will be sufficient space to permit of his effecting any necessary manipulation or adjustment of printing surfaces in the form. 110

In using the apparatus referred to, the

tube D will be positioned above the form B so that a space or blank in the printing surface of said form corresponding to a section of the finished work which is to be printed 5 from the form C, in a different color from the impressions obtained from the form B, or a sufficient portion of such a space, will be in alignment with the tube. An accurate and exact representation of such space or 10 portion thereof in alignment with the tube D will be projected through the tubes D, F, E, onto the base in the form C so that the necessary printing surfaces may be readily adjusted on said base as required 15 and secured in proper position in the form C.

If more than two impressions are required it will be evident that other forms, each containing the printing surface, or surfaces, required for any one color, will be successively 20 positioned beneath the tubular member E of the projecting apparatus in place of the form C and the type, etc., therein adjusted as required in conformity to the primary printing form B.

Instead of projecting a representation of the primary printing form, or a sufficient portion thereof, as above described, an impression printed from such form may be substituted for the form B.

Comparing Figs. 2 and 3, it will be seen that it is not necessary that the entire area of the primary form B, or impression therefrom, be projected onto the secondary form C, in order to accurately locate the position 30 in the latter of the printing surfaces c , c' , c^2 so that impressions therefrom will correctly register with the spaces b , b' , b^2 . It is only necessary that the projected image include a sufficient portion of the primary 35 form and the space b , for example, to enable the type or electrotype, constituting the printing surface c to be placed in the proper, corresponding, location in the secondary form C.

As the invention is primarily intended for use with large forms the projecting apparatus will be so supported that it can be readily shifted relative to the two forms, B, C, to bring different areas of the forms into 45 alignment therewith as required. In carrying out the method hereinbefore described, the low or cut-out portions of the electrotype or printing member to be positioned in the secondary form may be dusted or 50 powdered with a suitable white or light colored powder so that the high printing surface of such member will be clearly distinguishable, which will materially aid in 55 adjusting said printing member into the proper position. Generally, the apparatus will be used in a subdued light or slightly darkened room.

It is not necessary that the primary form or impression to be projected be supported 60 on the same table or level as the form for

effecting a subsequent impression. A modification of the construction described, as regards this feature, is diagrammatically illustrated in Fig. 5. Referring to this figure, it will be seen that the form or an impression 70 L therefrom is arranged on the lower face of a suitable support M positioned at a considerable distance above the imposing stone or table A. With such an arrangement all of the projecting apparatus can be 75 arranged within a single tube-like body N. As illustrated, the body N adjacent its upper end is provided with a lamp house or casing O and interiorly of said body is arranged a suitable lens system adapted to 80 project an image or representation of the illuminated area onto the form mounted on the table A.

While in the foregoing description it is pointed out that the invention is particularly adapted for use in positioning electrotypes in registering position, it will be evident that it is not limited to that particular use. For instance, the invention may be employed with equal advantage in positioning lithographic transfers. Also instead of employing a form or impression therefrom, an outline drawing or lay-out may be projected onto the secondary form to definitely define the boundary within which one or 90 more electrotypes, for example, must be positioned. As previously indicated, it is not necessary in every case to project an image of the entire space within which an impression from the adjustable printing surface 95 of the secondary form is to occupy in the finished work, but merely a sufficient amount of detail thereof to enable the operator to properly locate the electrotype in the secondary form. It is customary to include in 100 the primary form or impressions therefrom, or a drawing, certain "positioning points" and a projection of these, or a portion thereof, is all that is required.

The invention is also well adapted for 110 positioning dies for cutting and scoring sheets so that registration of the outlines produced thereby will register with printed matter on said sheets, and the term "impression form" used in the claims is to be 115 understood as covering any form which includes a movable or adjustable impression member, whether adapted to print, cut, score or otherwise act upon a sheet or blank.

Having thus described the invention what 120 I claim and desire to secure by Letters Patent is:

1. The herein described method of determining the correct position of a movable member in an impression form comprising displaying on the form an optical image of such necessary registering detail as to define the location for said member within the form. 125

2. The method of making up registering 130

- impression forms, each including a movable member, which comprises providing means containing suitable registering detail of a plurality of members of a form, projecting 5 onto the surface where the movable member is to be placed an image of a sufficient portion of said registering detail, and adjusting said movable member to bring corresponding parts thereof and of said image 10 into superposed relation.
3. The method of making up registering impression forms, each including a movable member, which comprises supporting above a form a representation of suitable registering detail, projecting onto the form an 15 image of a sufficient portion of said registering detail, and adjusting said movable member to bring corresponding parts thereof and of said image 20 into superposed relation.
4. The method of making up registering impression forms, each including a movable member, which comprises providing means containing suitable registering detail of a plurality of members of a form, illuminating 25 a suitable part of said registering detail, projecting onto the form an image of the illuminated area, and adjusting said movable member to bring corresponding 30 parts thereof and of said image into superposed relation.
5. The method of making up registering impression forms, each including a movable member, which comprises placing the form 35 on a suitable support, arranging above the form a representation of suitable registering detail, illuminating a suitable part of said registering detail, projecting onto the form an image of the said illuminated area,
- and adjusting said movable member to bring 40 corresponding parts thereof and of said image into superposed relation.
6. The combination with a support for an impression form, of means adapted to sustain above said support a representation 45 of suitable registering detail to indicate the proper position of a movable impression member in a form on said support, and means adapted to project onto said support an image of a sufficient portion of said 50 registering detail, for the purpose described.
7. The herein described improvement in the method of making up the secondary forms for use in multicolor printing comprising projecting an image of a sufficient 55 portion of a primary form or an impression therefrom, onto a second form to define the location for a printing surface in the secondary form, and securing such a surface in alinement with said image. 60
8. An apparatus for use in preparing printing forms for multicolor printing comprising a hollow body adapted to have its ends positioned in alinement with suitable areas of a primary form, or impression 65 therefrom, and a secondary form, means for illuminating the surface of the primary form, or impression therefrom, that is in alinement with one end of said body, and means within the body for projecting an 70 image of said illuminated surface onto the secondary form, for the purpose described.

In testimony whereof I affix my signature in presence of two witnesses.

ARTHUR K. TAYLOR.
